(57) CLAIM

The ornamental design for sport pants having a pattern thereon as shown and described.

DESCRIPTION

FIG. 1 is a front elevational view of sport pants having a pattern thereon showing our new design;

FIG. 2 is a left elevational view thereof;

FIG. 3 is a rear elevational view thereof; and,

FIG. 4 is a right elevational view thereof.

The portions of the drawing in broken lines show an environment of use and form no part of the claimed design.
